HEATER ATTACHMENT FOR AUTOMOBILES.

Application filed February 1, 1927. Serial No. 165,146.

This invention relates to improvements in heater attachments for automobiles, applicable to that class of heaters wherein air surrounding the engine exhaust manifold and heated thereby is conveyed by a duct through the dash of the automobile body into the seating compartment. The object of the improvement is to afford means of diverting the heated air in one direction or another in the compartment; distributing the heated air in said compartment more or less uniformly; or shutting off entirely the supply of heated air from entering said compartment.

In the usual practice the heated air enters the seating compartment directly from a duct that extends through the dash, which duct is controlled by a damper, and the heated air, when admitted to the compartment is confined more or less about the point of entrance which is generally located at one side of the dash. Thus, an excess of warmth is provided for one of the occupants, while another occupant seated along side of the former occupant is supplied with but little, if any warmth at all. The present invention contemplates supplying warmth for either one or both of the occupants in the seating compartment as may be desired.

These objects are accomplished by the construction illustrated in the accompanying drawings, in which:

Fig. 1 is a horizontal section of a construction embodying the invention;

Fig. 2 is an elevation projected from Fig. 1, a portion being broken away; and

Fig. 3 is an end view of the device positioned on the dash of an automobile, the dash being shown in section, there being included in the view a fragment of a duct through which heated air is conducted to the appliance.

The invention comprises an elongated case 1, one end 2 thereof being entirely open, and an outlet opening 3 being made in the bottom of the case near the end thereof opposite the open end 2. A sleeve 4 projects from the back 5 of the case and has communication through the back with the interior of the case. A vertical partition 6 is disposed in the case in line with the center of the sleeve which divides the case into two compartments 7 and 8 respectively.

A longitudinally movable damper 9, hav-

ing an opening 10 therein is disposed within the case 1 and is held flat against the back 5 thereof by means of guides 11, there being a projecting lip 12 at one end of the opening 10 that has contact with the partition 6 when the damper is moved outwardly and thereby limits outward movement of the damper.

The back 5 of the case has made therein an indentation 13, and the damper 9 has made therein a series of alined indentations 14, in which the indentation 13 in the back selectively projects accordingly as the damper is adjustably positioned, whereby the damper is retained in its various positions of adjustment.

In utilizing the invention the case is secured by any suitable means in position against the inner face of the dash 15 with the sleeve 4 protruding through the dash and extending into the duct 16 so as to have communication therewith. The duct 16 may be of any suitable form such as is ordinarily employed for conveying air heated by radiation from the manifold of the automobile engine, to the seating compartment. First, when the damper 9 is moved to its innermost position, as shown in Figs. 1 and 2, the adjacent end of the sleeve 4 is closed thereby and entrance of heated air from the duct into the case is thereby prevented; second, when the damper is moved outwardly to that position where the opening 10 of the damper reaches the partition 6, heated air passes from the duct into the compartment 7 from whence it passes through the outlet 3 into the seating compartment; third, when the damper is moved outwardly to a farther extent, so that its opening 10 is alined with the sleeve, heated air passes from the duct into both compartments 7 and 8 from whence it passes through the outlet 3 and the open end 2 of the case; and fourth, when the damper is moved to its outermost position, the lip or stop 12 bears against the partition 6, and the entrance of air from the duct into the compartment 7 is shut off by the damper which closes the corresponding portion of the sleeve, while air is admitted through the opening 10 in the damper into the compartment 8 and is directed through the open end 2 of the case into the seating compartment.

By this arrangement heated air may be supplied to different points or locations in the seating compartment simultaneously or

selectively, or, the supply of heated air may be shut off entirely, by manipulating the damper.

By positioning the case to one side of the dash, preferably back of the exhaust manifold, in front of one of the seats in the seating compartment, heated air is supplied from the compartment 7 to the feet of the occupant of the seat, the air being directed downwardly through the outlet opening 3, while heated air is directed laterally from the case through its open end toward the feet of the occupant of the adjoining seat. By adjusting the damper accordingly, the occupants of both seats may be supplied with more or less heated air as they may individually require for their comfort.

What we claim is:—

1. A heating appliance for an automobile having a hot air supply duct, a case positioned in the seating compartment of the automobile having communication with said duct, said case having therein a partition dividing the case into two compartments, there being a separate outlet for each of said compartments, and a sliding damper having an opening therein controlling communication between the duct and case, said opening being so located in said damper as to admit air from said duct selectively into the compartments of said case, or, into both accordingly as the damper is positioned, said

damper being also operable to shut off communication between the duct and case entirely.

2. In combination with an automobile having a hot air supply duct, a double compartment case having a separate outlet for each compartment; a connection with said duct having communication with said compartments; and a damper controlling communication between the duct and said compartments whereby air from said duct is selectively admitted to said compartments or to both of said compartments, or, the air is shut off entirely from said compartments accordingly as said damper is adjustably positioned.

3. In combination with an automobile having a hot air supply duct, a case located within the seating compartment of the automobile and having communication with said duct, said case having two separate outlets; a damper controlling communication between said duct and case; and a partition within said case whereby air from said duct is discharged from said case into the seating compartment selectively through said outlets, or through both of said outlets accordingly as said damper is positioned.

In testimony whereof we affix our signatures.

THEODORE KRESS.
